JAN BRONS AND NANNO TIMMER, OF NEAR DELFZYL, NETHERLANDS.

HYDROCARBON-ENGINE.

No. 868,839.

Specification of Letters Patent.

Patented Oct. 22, 1907.

Application filed July 1, 1904. Serial No. 214,827.

To all whom it may concern:

Be it known that we, JAN BRONS and NANNO TIMMER, both subjects of the Queen of Holland, and residents of near Delfzyl, in the Kingdom of the Netherlands, have invented a new and useful Hydrocarbon-Engine, of which the following is a specification.

The present hydrocarbon-engines of the four stroke cycle style may, as regards their working or utilization of the driving fluid, be divided into explosion-engines 10 and combustion-engines. In the explosion-engines a mixture of air and combustible is compressed and caused to explode during or after the passage through the dead point, while in the combustion-engines air alone is compressed up to a very high pressure and 15 after the passage of the crank pin through the dead point finely divided combustible is injected into the compressed air. In both cases an increase of the temperature of the burning mixture of air and combustible takes place and an expansion of the same, which 20 drives the piston forward and transmits power to the crank shaft.

The explosion-engines present the disadvantage, that the maximum pressure prevails in the cylinder only 25 after the passage of the crank pin through the dead point, so that the driving power produced is but imperfectly utilized and the wasted gases escape into the atmosphere while still possessing a considerable pressure and temperature. The combustion-engines, on the contrary, require a very considerable compression 30 of the air, so that the high temperature of the latter thereby produced causes a strong heating of the cylinder walls and consequently necessitates an increased cooling surface of the cylinder and a cooling power, which is in proportion increased.

35 Our invention relates to an improvement in four stroke cycle hydrocarbon-engines, whereby the said disadvantages are removed, the features of the explosion-engines and the combustion-engines being combined. In order to avoid the sudden, violent explosion caused by the ignition of a compressed mixture of air and combustible, the air is according to our invention compressed only to such a temperature while being mixed with a very small quantity of gasified combustible, that in the proximity of the dead point the 40 mixture is capable of igniting itself. The explosion thereby produced is very weak, but sufficient to cause an increase of the temperature within the working space of the cylinder and at the same time also an increase of the pressure of the ignited mixture. From this moment a further quantity of combustible is gradually injected and ignited to prevent the expanding mixture, which acts upon the piston, from cooling as long as the combustible is being supplied.

The object of our improvement is to provide an 45 injecting device with a spring-pressed valve and a shallow cylindrical box beneath the valve, which

box is provided along its periphery with a plurality of perforations at a certain height above the bottom. We attain this object by the hydrocarbon-engine illustrated in the accompanying drawing, in which— 60

Figure 1 is a vertical cross section through the hydrocarbon-engine, Fig. 2 is a vertical longitudinal section through the same, Fig. 3 is a plan of the top of the same, and Fig. 4 is a vertical longitudinal section on an enlarged scale through the injecting device. 65

Similar letters of reference refer to similar parts throughout the several views.

In the drawing we have shown a known four stroke cycle hydrocarbon-engine, but the construction of the same is quite immaterial. The cylinder *f* is shown as 70 provided with cooling ribs *f*¹ and the cover *q* as cast in one piece with a cylinder *q*¹, so as to form a cooling chamber through which the cooling water may be passed in any known manner. The cover *q* is provided with an air-inlet *g*² and an outlet *h*². The casing *u* is shown as closed and provided with a ventilating pipe *u*¹, but this is quite immaterial to my invention. The cavity of the cover *q* is covered with a plate *v*, through which the cylindrical valve boxes of the air-inlet valve *g* and the outlet valve *h* are introduced into the respective bores of the cover *q*. A holding down plate *w* and various studs with nuts serve for securing these cylindrical valve boxes. The valve box *i*² of the injecting device shown at Fig. 4 is also inserted in the cover *q* and there secured in any known and approved manner. 75

The spindles *g*¹ and *h*¹ of the air-inlet valve *g* and the outlet valve *h* respectively are pressed upwards by the helical springs shown in Fig. 2, so as to normally close the valves. The injecting valve *i* is also pressed upwards by a helical spring *i*². A spindle *i*¹ passing 80 through a stuffing box *i*⁴ and the valve box *i*² is adapted to act upon the spindle of the valve *i* for opening the latter. The small chamber *i*³ above the injecting valve *i* is in any known manner connected with a pipe *x*, which supplies the liquid combustible. A shallow box *m* is shown as fastened beneath the valve *i* on the valve box *i*² by means of a screw-thread and it is provided along its periphery with several holes *n* at a certain small height above its bottom. The crank shaft *a* carrying two fly wheels *a*¹ *a*² is arranged to drive in any 85 known manner a cam shaft *b* at such a rate, that the latter makes but one revolution on every two revolutions of the crank shaft *a* as usual. On the cam shaft *b* are three suitable cams placed, of which in Fig. 1 only two are visible and denoted by *b*¹ and *b*² respectively. 90 When assuming the cam shaft *b* to turn in the direction of the arrow, then the cam *b*² may serve for opening the outlet valve *h* during the fourth piston stroke or nearly so, while the cam *b*¹ serves for opening the injecting valve *i* during the first piston stroke or nearly so and the third cam (which is not visible in Fig. 1 as it is covered by the cam *b*¹) serves for opening the air-inlet 95 100 105 110

- 22
- valve g during the first piston stroke or nearly so. Above the cam shaft b an axle y is disposed in the casing u and three levers y^1 carrying rollers z are mounted to rock on the axle y . In Fig. 1 the three levers y^1 are assumed to occupy the same position, their rollers z resting on the cylindrical part of the cams, so that only one of them is visible. An axle l is shown as provided in suitable supports l^1 l^2 on the plate v and on this axle l three two-armed levers c , d and e are mounted to rock.
- 10 The external arms of the three levers c , d and e are pivotally connected with three rods c^1 , d^1 and e^1 respectively, which are guided in suitable holes of the casing u and can be acted upon by the three cams b^1 b^2 with the aid of the three rollers z and the three levers y^1 .
- 15 The internal arms of the two levers c and e are provided at their free ends with adjustable screws c^2 and e^2 , which can act upon the spindles h^1 and g^1 of the outlet valve h and the air-inlet valve g respectively. The internal arm of the third lever d is much shorter than those of 20 the two first levers c^1 and e^1 and carries an adjustable screw d^2 , which can act upon the upper end of the spindle i^1 of the injecting device (see Fig. 4).
- 25 The hydrocarbon-engine is operated as follows: If the hydrocarbon-engine is small, its two fly wheels a^1 a^2 may be turned with one's hands several times, so that air is first sucked in through the inlet g^2 and the valve g (the latter being opened from the respective cam b^1 by means of the roller z , the lever y^1 , the rod c^1 and the two-armed lever e) during the first stroke of 30 the piston k downwards, then after closing the valve g the air is compressed during the second stroke of the piston k upwards, afterwards the compressed air is allowed to expand during the third stroke of the piston k downwards and at last the expanded air is allowed 35 to escape through the opened outlet valve h during the fourth piston stroke upwards. As the clearance is very small, of course the air will be strongly compressed during the second piston stroke, so that it attains a very high temperature and strongly heats the 40 walls of the cylinder f and the cover g . After a certain number of revolutions of the crank shaft a the cylinder f and the cover g will have been brought to a sufficiently high temperature. At this moment the turning of the two fly wheels a^1 a^2 is discontinued and the supply of 45 liquid combustible through the pipe x is turned on, so that during the first piston stroke downwards not only air is sucked in through the opened inlet valve g into the cylinder f , but also a small quantity of liquid combustible is sucked in through the opened valve i 50 into the box m which it fills about up to the holes n n . Owing to the high temperature of the box m a part of this quantity is gasified while being sucked through the holes n n into the cylinder. In other words, a very small quantity of the combustible will be injected in its gasified state into the air within the cylinder f and mixed therewith. The greater part of the combustible, however, remains behind in its liquid state within the box m . On the piston k reaching its lowermost position it will be again moved upwards by 55 the live force of the two fly wheels a^1 a^2 , to compress the weak mixture of air and combustible during the second piston stroke. In the proximity of the uppermost position of the piston k the compressed weak mixture will attain so high a temperature as to be 60 capable of igniting itself, when a weak explosion and an increase of the temperature and the pressure will follow. This explosion exerts its influence upon the piston k but is still overcome by the live force of the two fly wheels a^1 a^2 , so that temperature and pressure of the product may be a little further increased. After 70 the passage of the crank pin through the dead point the exploded mixture will drive the piston downwards during the third stroke, while the combustible in the box m is gradually forced out partly in its gasified state (due to the heat of the box m and the product) 75 and partly in its liquid state either through the shock due to the explosion, or through the sucking effect of the piston. The combustible thus gradually injected constantly mixes with the excess of the hot air and sustains the combustion, so that not only the mixture 80 is prevented from cooling, but also the driving power is constantly supplemented and the piston k is moved downwards more uniformly than hitherto. The injection of the combustible into the cylinder through the holes n n of the box m continues, until all the combustible has been extracted from the box m . During 85 the fourth stroke the piston k is forced upwards by the live force of the two fly wheels a^1 a^2 and the outlet valve h is opened to permit the wasted gases to escape. Afterwards all the occurrences described above will 90 repeat.
- 95 Care should be taken in designing the injecting device, that the box m be made only large enough for containing the quantity of liquid combustible, which is required for a cycle. The valve gear should be so proportioned, that the above condition may be fulfilled.
- The hydrocarbon-engine described so far may be varied in many respects without departing from the 100 spirit of our invention.
- What we claim as our invention, and desire to secure by Letters Patent, is—
1. In a four stroke cycle hydrocarbon-engine, the combination with a spring-pressed inlet-valve for liquid combustible, of a shallow box beneath and surrounding said spring-pressed inlet-valve within the cylinder and provided along its periphery with a plurality of holes at a small height above its bottom, it being adapted to contain up to its holes the quantity of liquid combustible required for a cycle. 110
2. In a four stroke cycle hydrocarbon-engine, the combination with a spring-pressed inlet-valve for liquid combustible, of a space above said spring-pressed inlet-valve, a channel adapted to conduct the liquid combustible to said space, means controlled from the crank shaft for periodically opening said spring-pressed inlet-valve, and a shallow box beneath and surrounding said spring-pressed inlet-valve within the cylinder and provided along its periphery with a plurality of holes at a small height above its bottom, it being adapted to contain up to its holes 115 the quantity of liquid combustible required for a cycle. 120
3. In a four stroke cycle hydrocarbon-engine, the combination with a cylinder, of an inlet-valve adapted to admit air into said cylinder a spring-pressed inlet-valve adapted to admit liquid combustible to said cylinder, an outlet-valve adapted for allowing the spent gases to escape from said cylinder, means for periodically opening said inlet-valve, said spring-pressed inlet-valve and said outlet-valve, a shallow box beneath and surrounding said spring-pressed inlet-valve within said cylinder and provided along its periphery with a plurality of holes at a small height above its bottom, said shallow box being adapted to contain up to its holes the quantity of liquid combustible required for a cycle. 125
4. In a four stroke cycle hydrocarbon-engine, the combination with a cylinder, of a spring-pressed inlet-valve 130

for liquid combustible, and a shallow box beneath and surrounding said spring-pressed inlet-valve within said cylinder and provided along its periphery with a plurality of holes at a small height above its bottom, said shallow box being adapted to contain up to its holes the quantity of liquid combustible required for a cycle.

5. In a four stroke cycle hydrocarbon-engine, the combination with a cylinder of a spring-pressed inlet-valve for liquid combustible, a space above said spring-pressed inlet-valve, a channel adapted to conduct the liquid combustible to said space, means controlled from the crank shaft for periodically opening said spring-pressed inlet-valve, and a shallow box beneath and surrounding said spring-pressed inlet-valve within said cylinder and provided along its periphery with a plurality of holes at a small height above its bottom, said shallow box being adapted to contain up to its holes the quantity of liquid combustible required for a cycle.

10. 6. In a four stroke cycle hydrocarbon-engine, the com-

bination with a cylinder, of an inlet-valve adapted to 20 admit air into said cylinder, a spring-pressed inlet-valve, adapted to admit liquid combustible to said cylinder, an outlet-valve adapted for allowing the spent gases to escape from said cylinder, means for periodically opening said inlet-valve, said spring-pressed inlet-valve and said 25 outlet-valve, a shallow box beneath and surrounding said spring-pressed inlet-valve within said cylinder and provided along its periphery with a plurality of holes at a small height above its bottom, said shallow box being adapted to contain up to its holes the quantity of liquid 30 combustible required for a cycle.

In testimony whereof we have signed our names to this specification in the presence of two subscribing witnesses.
